UNITED STATES PATENT OFFICE.

JOHN H. GUEST, OF BROOKLYN, NEW YORK.

ELECTRIC LAMP.

SPECIFICATION forming part of Letters Patent No. 233,346, dated October 19, 1880.

Application filed February 27, 1880.

To all whom it may concern:

Be it known that I, JOHN H. GUEST, of Brooklyn, in the county of Kings and State of New York, have invented an Improvement in 5 Electric Lamps, of which the following is a specification.

Electric lamps have been made with carbon, platina, and other material in the circuit, rendered incandescent by the passage of the 10 current, and such conductors have been placed within a glass bulb that is exhausted of air; and in an application heretofore filed by me 15 cups or receptacles for mercury are made upon the glass of the bulb, and through these the conductors pass.

In all instances where the wires pass through the glass there is risk of the glass being broken, or of the wire becoming smaller and allowing air to pass between it and the glass. This 20 arises from the wire expanding by heat, and where the glass is strong enough to withstand that expansion the wire is increased in diameter while hot, and when it cools the wire becomes smaller and shrinks away from the 25 glass. The object of the mercury-seal is to prevent air passing in between the wire and glass.

My present invention is a still further improvement in the same line. I employ groups 30 of wires, each having two or more very fine wires passing through the glass, and these are bunched or twisted together to form the pairs of conductors, and the mercury also is applied as before. By this improvement the electric 35 current is diffused through the two or more fine wires. Hence each wire takes a smaller proportion of the current than it would if only one conductor were used, and the heat is not as great as heretofore, and the expansion is 40 less in proportion; and as the wires used are so much smaller the expansion is reduced to a minimum.

In the drawings, Figure 1 is a section of my 45 improved lamp, and Fig. 2 is a section of the glass where the wires pass through separately.

The glass bulb *a* is of usual character, and at *b* *c* are the cups for the mercury-seals *d* to the metallic conductors *f* *g*, and *h* represents the carbon that is rendered incandescent by 50 the passage of the electric current.

The carbon is to be connected to the con-

ductors in any desired manner. I have shown the conductors as made into loops, in which the carbon is suspended.

It sometimes happens that the carbon becomes injured and the lamp useless. To guard against this I make a carbon-holder, *i*, of glass, at one side of the bulb *a*, and in this holder there are carbons in any suitable number, and the orifice *o* between *a* and *i* allows 55 for one carbon at a time being shaken into the loops or holders of the conductors without injury to the vacuum in the bulb.

The conductors *f* and *g* are each composed of two or more fine wires, for the reasons and 65 with the object before mentioned.

Sometimes I twist the two or more wires together, and pass them in that condition through the glass, as seen in Fig. 1, care being taken to melt the glass into the spaces between the 70 wires. In other instances the wires are in a more open condition, but having sufficient twist to prevent the lengthening of the wires at each surface of the glass, the expansion being in the direction of the circumference of the 75 helix. In other instances these very fine wires pass through the glass straight, as seen in Fig. 2, and are afterward twisted or bunched together where they are united to the incandescent conductor, and also within or near the 80 mercury-seal.

In cases where the bulb contains gas that will not injure the incandescent body, said gas is confined by the mercury-seal, applied, as aforesaid, around the conductors. 85

I claim as my invention—

1. In an electric lamp, two or more very fine wires passing through the glass and grouped together to form each of the conductors leading to the incandescent light-giving body, for 90 the purposes and substantially as set forth.

2. The combination, with an exhausted glass bulb and the electric conductors, of a carbon-holder of glass at one side of the bulb and an opening from the same into the bulb, substantially as set forth. 95

Signed by me this 26th day of February, A. D. 1880.

J. H. GUEST.
